(57) **CLAIM**

The ornamental design for a tire tread, as shown and described.

DESCRIPTION

FIG. 1 is a front perspective view of a tire tread of the present application;

FIG. 2 is a front elevation view thereof;

FIG. 3 is a right-side view thereof;

FIG. 4 is a left-side view thereof;

FIG. 5 is a rear perspective view thereof;

FIG. 6 is an enlarged front perspective view of FIG. 1, showing a portion thereof;

FIG. 7 is an enlarged front elevation view of FIG. 2, showing a portion thereof; and

FIG. 8 is an enlarged right side view of FIG. 3, showing a portion thereof;

FIG. 9 is an enlarged left side view of FIG. 4, showing a portion thereof; and,

FIG. 10 is an enlarged rear elevation view of FIG. 5, showing a portion thereof.

In the drawings, the broken lines depict environmental subject matter only and form no part of the claimed design.

1 Claim, 10 Drawing Sheets
